UNITED STATES PATENT OFFICE.

DAVID J. CANCHESTER, OF CHICAGO, ILLINOIS.

IGNITER.

1,134,314.

Specification of Letters Patent. Patented Apr. 6, 1915.

Application filed February 3, 1913. Serial No. 745,853.

To all whom it may concern:

Be it known that I, DAVID J. CANCHESTER, a citizen of the United States, residing at Chicago, in the county of Cook and State 5 of Illinois, have invented certain new and useful Improvements in Igniters, of which the following is a specification.

My invention relates to igniters and has for its primary object the provision of an 10 improved igniter which shall have improved means for igniting inflammable material.

With the above and other objects in view, this invention consists substantially in the combination, arrangement and construction 15 of parts, all as hereinafter described, shown in the accompanying drawings which form a part of this specification and show the preferred embodiment of my invention, and more specifically set forth in the subjoined 20 claims.

In my igniter, I employ the well known elements of a striking or scraping body having a roughened surface, and a body of spark-producing material contacting with 25 the roughened surface to produce sparks. The sparks thus produced may be projected against any explosive gas or any other body of material which is desired. If, however, a flame is desired instead of sparks, I provide a wick and suitable means for supplying 30 the wick with a volatile liquid whose gas is highly inflammable, together with means for directing a shower of sparks against the wick to ignite it.

I preferably embody my invention in an 35 elongated cylindrical case, readily insertible in the ordinary pocket of wearing apparel and composed of two main members, a body portion containing the wick and receptacle 40 for an inflammable liquid, and a cap portion slidably hinged to the body portion and containing the spark producing mechanism. By the interposition of a wall of metal between the spark-producing mechanism and 45 the chamber for inflammable liquid, I separate the spark-producing mechanism from the liquid and the gases emanating therefrom.

The production of sparks from my device 50 is preferably accomplished by the mere oscillation and release of a small lever. In my construction, I position the spark-producing device above the wick holding portion of the case and in a chamber separated from 55 the wick chamber, but when it is desired to

light the wick the cap may be removed from its position upon the body portion of the case, swung upon its hinge and lowered to such a position that the shower of sparks will be projected directly across the wick to 60 ignite it. The hinge pivot is secured at its upper end to a lug upon the cap, and free to slide in a lug upon the body portion of the case. Preferably the hinge pivot depends below the lower, or body lug, and 65 bears a small ball at its lower extremity, thus forming a convenient clip for securing the igniter in the pocket of the user.

In the drawings:

Figure 1 is a side elevation of my invention; Fig. 2 is an enlarged vertical section of my invention showing some parts in elevation; Fig. 3 is an elevation of my invention showing an adjusted position of the parts; Fig. 4 is a view of a portion of my 70 invention showing parts of the case broken away, a portion of the case in section and an elevation of portions of a spark-producing device; Fig. 5 is a section taken on the line 5-5 of Fig. 4 and looking in the direction indicated by the arrows; Fig. 6 is a top plan view of a portion of a spark-producing device showing the casing of my invention 75 in section; Fig. 7 is a side elevation of a portion of the spark-producing device showing parts of my invention broken away and parts thereof in section. 80

The casing of my invention is formed of two main portions, the lower of which is indicated by reference numeral 10 and the 90 upper one by 11. The two parts of the casing are preferably so constructed that the portion 11 descends about and is removably fixed in relation to the lower portion 10. The casing 11 is provided with a lug 12, 95 to which is rigidly secured a hinge pin 13. The lower portion 10 of the casing bears an apertured lug 14, through which the hinge pin 13 passes and in which the hinge pin is free to slide. The hinge pin 13 projects below the lug 14, as at 15, and preferably bears upon its lower extremity a globular enlargement 16, the extremity 15 and the enlargement 16 constituting a 100 pocket clip for securing my invention to the ordinary pocket in wearing apparel.

Preferably, the inner diameter of the casing 11 is sufficient to allow it to descend upon the upper extremity of the casing 10 and removably secure the two together. A 110

web 17 secured within the casing 11 forms a closure therefor, the portion of the casing which descends about the member 10 depending below this web 17. It is seen, therefore, that when the members 10 and 11 are sheathed together their respective chambers are separated and the liquid and gases contained in the chamber of the member 10 cannot pass into the chamber of the member 11.

Secured in the member 11 is the spark-producing portion of my invention. The frame 18 of the spark-producing portion is secured to the casing 11 preferably by the ordinary well-known means of pins 41 and bayonet slots 42. Two arms 19 and 20 depend from the frame 18 at diametrically opposite sides thereof, and a horizontal pin 21 is rigidly secured at each of its ends in one of these arms. A centrally bored wheel shaft 22 is mounted for oscillation upon the pin 21 and is slotted, as at 23, from its outer to its inner periphery, the slot being of sufficient size to admit of the insertion of a spring member 24. Mounted for rotation upon the wheel shaft 22 and disposed preferably in the center of the casing 11 is a striking wheel 25, the outer periphery of which is roughened preferably by serrations 26. The center of this wheel is cut away and the inner periphery bears a plurality of ratchet points 27. The spring member 24 is at one of its ends secured in fixed relation to the wheel shaft 22 and its free end extends out of the slot 23 for engagement with the ratchet points 27, sufficient room being allowed between the outer periphery of the wheel shaft 22 and the ratchet points 27 to admit of the passage of the spring member 24. The free end of the spring member 24 is adapted, when the wheel shaft is turned in one direction, to press against and slide upon the inner periphery of the striking wheel 25 and when the wheel shaft 22 is turned in the opposite direction the free end of the spring member 24 contacts with the ratchet points 27, locking the wheel shaft 22 and the striking wheel 25 into fixed relation and causing the striking wheel to oscillate with the wheel shaft. The oscillation of the wheel shaft 22 is accomplished by the manual swinging of a lever 28, which is secured to the end 29 of the wheel shaft 22 and extends without the casing 11, a slot 30 being provided in the casing 11 for the oscillation of the lever 28. To provide a smooth bearing surface for the hand of the operator, I preferably place a globular enlargement 31 or other smooth end upon the outer extremity of the lever 28. A tension spring member 32 is given a convenient number of loose turns around the wheel shaft 22, and has one of its ends fixed in relation to the arm 20 of the frame 18 and its opposite end secured in relation to the wheel shaft 22. The downward oscillation of the

lever 28 turns the wheel shaft 22 upon the pin 21, sliding the spring member 24 within the striking wheel 25 to a point where it slips over and contacts with one of the ratchet points 27. This oscillation of the lever 28 places tension upon the spring member 32, and the removal of the hand of the operator from the lever 28 releases the power thus stored in the spring member 32, causing the wheel shaft 22 to oscillate in a reverse direction carrying with it the striking wheel 25 to which it is locked by the spring member 24. In this manner, a sudden and violent rotation of the striking wheel 25 is obtained. For securing one end of the tension spring 32 in fixed relation to the wheel shaft 22, I preferably employ a washer 33 embracing the wheel shaft and keyed thereto as at 35, the end of the spring member 32 being positioned against an offset lug 34 upon the washer 33.

The frame 18 is centrally bored, as at 36, for the insertion of a piece of spark-producing material 37. A cap 38 in threaded engagement with the upper extremity of the frame 18 forms a stop for one end of a compression spring member 39, the opposite end of which bears against the spark-producing piece 37 forcing it downward into contact with the striking wheel 25. Adjustment of the pressure of the piece 37 against the wheel 25 is obtained by turning the cap 38 upon the frame 18. The violent rotation of the striking wheel 25 above described causes its serrations 26 to chip particles of spark-producing material from the piece 37 and projects the sparks thus formed through an opening 40, provided therefor in the casing 11.

A chamber 43 is formed by the casing 10 and contains a wick 44 secured in position within the chamber preferably by a packing of an absorbent material 45, such as cotton. A web 46 forms a closure for the lower extremity of the chamber 43, and the body portion of the casing 10 extends below the web 46, as at 47, to form a socket or any other suitable device for convenience in securing my invention to the end of a pen, pencil or any other desired article. A collar 48 is provided for the upper extremity of the wick 44 for convenience in maintaining this end of the wick in its proper position in the chamber 43 and slightly elevated above the packing material 45. The casing 10 projects upwardly from the upper extremity of the packing material 45 and the wick 44, to provide a sheath for engagement with the inclosing portion of the casing 11, and also to provide a guard from the wind for the flame produced at the end of the wick. Preferably, the casing 10 is apertured as at 49 to furnish a supply of air to the wick 44 to assist combustion. Opposite the upper extremity of the wick, the casing

10 is cut away as at 50 to allow the passage of a shower of sparks from the spark-producing device to the wick.

In the operation of my invention, the 5 manual oscillation of the lever 28 as heretofore described produces a shower of sparks, which are projected without the casing 11 through the opening 40. If it is desired to ignite a substance which will burst 10 into flame by contact of hot sparks, the opening 40 is placed adjacent the substance to be ignited, the lever 28 oscillated and released and the resulting shower of sparks directed toward the substance. If, however, 15 a flame is desired, the casing 11 is unsheathed from its position upon the casing 10 (as in Fig. 1), turned upon its hinge and lowered until it assumes the position shown in Fig. 3 beside the upper portion of 20 the casing 10. In this position, the shower of sparks is projected directly against the upper extremity of the wick 44 through the opening 40 in the casing 11, which produces a flame upon the wick. When it is desired 25 to extinguish the flame, the casing 11 may be raised, swung upon its hinge and replaced in its position upon the casing 10.

In the accompanying drawings and in the foregoing description are set forth the 30 preferred embodiment of my invention, but it is obvious that one skilled in the art may make modifications thereof without departing from the principle of the invention.

I claim:

- 35 1. The combination of a wick and its container, and a spark-producing device and its casing, the container and the casing being removably sheathed one with the other and slidably hinged together.
- 40 2. The combination of a wick, a tubular container therefor, a spark-producing device, a tubular casing therefor removably sheathed upon said container, a web forming a closure for the casing, an apertured 45 lug upon the container, and a hinge pin secured to the casing and slidably pivoted in the apertured lug.
- 50 3. The combination of a wick, a tubular container therefor, a spark-producing device, a tubular casing therefor removably sheathed upon said container, a web forming a closure for the casing, an apertured lug upon the container, a hinge pin secured 55 to the casing and slidably pivoted in the apertured lug, and means for securing the container and the casing to a relatively thin material comprising an extension upon the free extremity of the hinge pin in close proximity to the body of the container.
- 60 4. The combination of a wick, a container therefor having an aperture adjacent one extremity of the wick, a spark-producing device, a casing therefor having an opening for the passage of sparks produced, a tubular extension upon the casing into which

the container is removably sheathed, and means connecting the container and the casing for positioning the opening of the casing opposite the aperture of the container.

5. The combination of a container having 70 an aperture for the passage of sparks adjacent its outer extremity and having air holes adjacent its upper extremity, a wick therein having its upper extremity opposite said aperture and adjacent said air holes, a spark-producing device, a casing therefor having an opening for the passage of sparks produced and slidably hinged to the container, one end of said container being removably sheathed with one end of said casing, and means connecting the casing and 80 the container for positioning the spark opening opposite the spark aperture.

6. The combination of a container having 85 an aperture for the passage of sparks adjacent its outer extremity and having air holes adjacent its upper extremity, a wick therein having its upper extremity opposite said aperture and adjacent said air holes, a spark-producing device, a casing 90 therefor having an opening for the passage of sparks produced, one end of said container being removably sheathed with one end of said casing, means connecting the casing and the container for positioning 95 the spark opening opposite the spark aperture, and a web separating the container from the casing.

7. The combination of a wick, a container 10 therefor having a spark aperture opposite one extremity of the wick, a casing removably sheathed with the container having its sheathed extremity closed from communication with the container and having a lever slot and a spark opening, a spark-producing 10 device within the casing, an operating lever for the spark-producing device protruding without the casing through the lever slot, and a device connecting the container and the casing for positioning the spark opening opposite the spark aperture.

8. In an igniting device, a tubular body and a wick chamber therein in combination with a cap swiveled to and movable lengthwise of said body, a friction wheel mounted 115 on the cap, a lever handle rigidly attached to and projecting radially beyond the wheel, and a stick of sparking material housed in the cap and spring pressed toward the friction wheel.

9. In an igniting device, the combination of a tubular body having a wick chamber at one end and a pencil holder at its other end, with a cap for the wick chamber swiveled to and movable lengthwise of the tubular body, and a sparking member carried by and movable with the cap.

10. In an igniter, a tubular body containing a wick chamber, in combination with a cap constituting a cover for said chamber,

a stem attached to the cap and passing through a tubular lengthwise bearing on the side of the tubular body, in which it can both swivel and move lengthwise, and a 5 sparking member carried by and movable with said cap.

In testimony whereof I have signed my

name to this specification, in the presence of two subscribing witnesses, on this 31st day of January, A. D. 1913.

DAVID J. CANCHESTER.
